UNITED STATES PATENT OFFICE.

HOMER H. POOLE, OF PARSONS, KANSAS. ASSIGNOR OF ONE-HALF TO SIDNEY E. GLOYD, OF PARSONS, KANSAS.

CONVERTIBLE VEHICLE-BODY.

1,367,669.

Specification of Letters Patent.

Patented Feb. 8, 1921.

Application filed December 31, 1919. Serial No. 348,565.

To all whom it may concern:

Be it known that I, HOMER H. POOLE, a citizen of the United States, residing at Parsons, in the county of Labette and State of 5 Kansas, have invented certain new and useful Improvements in Convertible Vehicle-Bodies, of which the following is a specification.

My invention relates to improvements in 10 vehicle bodies adapted for use in connection with motor trucks and farm and other wagons, whereby I am enabled to readily convert the body into a tight receptacle or box for conveying grain and the like, or 15 into a flat platform for hauling hay, fodder or other loose material. In the increased use of motor trucks particularly, as is understood, they are rendered more efficient when the bodies thereof may be arranged or ad- 20 justed for various purposes, and my object is to render such structures quickly and simply convertible, as hereinabove indicated, so that in each changed condition the parts thereof will remain in positively fixed po- 25 sition without liability of disarrangement, all as will be hereinafter more particularly pointed out.

In the accompanying drawing, which forms a part hereof, Figure 1 is a vehicle body in 30 perspective showing my improvements applied thereto; Fig. 2 an elevation of one of the brace rods and anchoring members which I employ; Fig. 3 a side elevation thereof, and Fig. 4 is a view showing said parts in 35 collapsed position.

In said drawing, the portions marked, 5, indicate my improved sill, which is preferably of a compound character to embody a guideway or groove, and is composed of 40 any suitable material for the purpose. Several of such sills are employed without limit as to the number in accordance with the size of the body to which they are applied, and as indicated in Fig. 1, they may comprise 45 two longitudinally spaced members, 6, 7, or, as will be understood, they may be made of a single channeled structure, and positioned beneath the floor, 8, of the bed for supporting the same. It will be understood, of 50 course, that said bed is provided with forward and rear end portions, 9, 10, or otherwise, of any desired character. To the side walls, 12, of the body I secure a series of brace-rods, 13, terminating in a preferably 55 curved end, 14, which rods are mounted in

the guideways 5' of the sills 5, the number of such rods corresponding to the number of sills employed. The upper ends of said rods 13 have integrally formed therewith or secured thereto stake pockets, 15, for a purpose which will appear. Pivottally connected to said rod 13 in a bracket, 16, forming part thereof, is an anchoring member, 17, which rod and member constitute in effect a hinge, said anchor also being seated 65 in the guideway in sill members 6, 7.

When arranging the elements of a vehicle body to produce a tight box-like formation, the side wall 12 is preferably placed upon the sills 5 in the position indicated in Fig. 4 with the hinge members 13, 17, collapsed, in which position they are inserted into the guideway 5' substantially as indicated, for illustration, between the sill members 6, 7, the curved or hooked end 14 of the brace 13 (indicated in dotted lines) being passed over a cross-pin, 18, the anchor member 17 passing below said pin and being retained in horizontal position by the end clip, 20, said clip embodying an eccentric formation, as 80 21, for a purpose to be explained. When so arranged said side wall 12 is raised to the position indicated in Fig. 3, where it will be seen that it is standing upon the floor 8 of the bed, which operation causes the hooked end 14 of rod 13 to automatically catch about pin 18. When this is accomplished, anchor rod 17 is forced outwardly, its lower end passing through the eccentric portion 21 of clip 20 to the outer end of the latter, 90 and, as said lower end of the anchor impinges against said clip, there is a binding action between these members by which said anchor 17 is retained in the position indicated in Fig. 3. However, as a further 95 means of security in maintaining said parts in positively fixed position, I may employ a pin, as 22, carried by a chain, as 22', which passes through sill 5 and said anchor 17, but it will be understood that any suitable 100 means may be employed for retaining said anchor in its outer position other than said clip and pin. When thus positioned said wall is positively retained in its upright position indicated in Fig. 3, so that the as- 105 semblage of the ordinary two side walls in connection with the forward and rear ends employed in vehicle bodies results in a rigidly retained tight compartment.

When the vehicle is desired for embody-

ing an open platform arrangement, the anchor 17 is released and forced inwardly through the guideway in the sill toward rod 13, when the side walls 12 can be brought 5 to the position indicated in Fig. 4, and free to be slided back and forth on the sills, but in order to prevent material displacement thereof, and insure a tight fit between it and the floor 8, I provide means for se-
10 curing the same in locked position, that illustrated being the hole, 23, which regis-
ters with a similar hole, in the sill 5, through which the pin 22 may be inserted for holding said walls in fixed position horizontally
15 to the floor 8, as indicated in Fig. 4, where it will be seen in dotted lines that the hinge members 13 and 17 extend under the floor 8 and act as levers thereagainst for main-
taining the wall 12 in stable position. When
20 such adjustment has been made it will be readily understood that pocket stake 15 is in horizontal position so that an ordinary stake may be inserted therein when such ar-
rangement is desired. It will be seen also
25 that the sills 5 project beyond each side of the floor so that when the walls 12 are let down into platform position, ample sup-
port is provided therefor by the sills to insure that a strong and fixed broad platform
30 is obtained by means of the mechanisms co-
operating with said sills for rigidly locking said walls in position.

I am aware that convertible bodies for vehicles have been proposed, which I do not 35 claim broadly, my improvements relating more particularly to the sills substantially of the character disclosed in connection with the combined hinge braces and walls, which accomplish the double purpose of
40 maintaining the walls of the vehicle in vertical and horizontal positions as indicated, and by which such body may be readily converted for the uses stated.

I claim as my invention:

45 1. In a convertible vehicle body, a sill embodying a guideway, a wall, a hinge se-
cured to said wall for supporting the same in position, said hinge being collapsible and nesting in said sill when said wall is in
50 horizontal position, and means for retaining said hinge in fixed position.

2. In a convertible vehicle body, a floor, a sill embodying a guide-way projecting at opposite sides of said floor, a wall adapted to be mounted upon said floor, 55 a hinge fixedly secured to said wall and movably mounted in said sill, and means for fixedly securing said hinge to rigidly support said wall in upright position and for releasing said hinge to permit col-
lapsion thereof to position said wall in horizontal relation to said floor.

3. In a convertible vehicle body, a floor, a sill embodying a guide-way for supporting said floor, a swinging wall, a collapsible hinge secured to said wall and retained within said guide-way to maintain said wall in fixed horizontal relation to said floor, means for releasing said hinge to permit said wall to be swung into vertical po- 70 sition upon said floor, and means for fixedly securing said hinge in said latter po-
sition.

4. In a convertible vehicle body, a sill embodying a guide-way, a floor mounted 75 thereon, a wall adapted to be mounted vertically upon and horizontally alongside said floor, a brace secured to said wall and hav-
ing a locking end, means in said sill with which said brace engages, an anchor pivot-
ally connected to said brace adapted to swing inwardly and outwardly in relation to said sill, and means on said sill for se-
curing said anchor in fixed position when 80 said wall is in upright position and releas-
ing the same when said wall is lowered to horizontal position in relation to said floor.

5. In a convertible vehicle body having a floor and walls, a sill embodying a guide-way for supporting said floor, a hinge com-
prising a brace secured to said wall and a swinging anchor member connected thereto, 85 said hinge being adapted to be retained within said guide-way and means in said sill for frictionally engaging the ends of 90 said anchor when said wall is in upright position and whereby said anchor may be forced inwardly to collapse said hinge and permit said wall to be placed in horizontal position.

In testimony whereof I affix my signature.
HOMER H. POOLE.
